A. W. MITCHELL

DISPENSING APPARATUS

Filed Sept. 2, 1922

INVENTOR

ALBERT W. MITCHELL,

BY

Arnold Farrel
ATTORNEY

UNITED STATES PATENT OFFICE.

ALBERT W. MITCHELL, OF NEW HAVEN, CONNECTICUT, ASSIGNOR TO GEORGE H. BROWNE, OF NEW HAVEN, CONNECTICUT.

DISPENSING APPARATUS.

Application filed September 2, 1922. Serial No. 585,923.

To all whom it may concern:

Be it known that I, ALBERT W. MITCHELL, citizen of the United States, and resident of New Haven, in the county of New Haven and State of Connecticut, have invented certain new and useful Improvements in Dispensing Apparatus, of which the following is a specification.

This invention relates to dispensing apparatus and is applicable more particularly to holy water or blessing fonts used for devotional purposes.

According to the invention, an efficient apparatus can be produced which will meet all the requirements of sanitation, noiseless operation and expeditious self-service when the apparatus is intended to be operated in turn by each member of a congregation of persons desirous of obtaining a drop of holy water necessary for the performance of a devotion.

Previously to this invention dispensing apparatus have been proposed having means whereby, upon operation of the same, a determined quantity of air is admitted into a hermetically closed reservoir containing a liquid and the air admitted permits flow, by gravity alone, of a corresponding quantity of liquid. The action of such means, however, is not positive and therein differs from the improved means which are designed to act positively and eject a determinable uniform quantity of water at each operation, regardless of the force or speed exercised by the operator when the operation is effected.

The means for discharging positively or ejecting a measured quantity of liquid is the chief differentiating characteristic of the improved apparatus and this means will be particularly described hereinafter and set forth in the appended claims, together with other novel features constituting part of this invention.

The accompanying drawings illustrate an embodiment of the invention and in these drawings—

Figure 1 is a perspective view showing a design of casing which is appropriate for use as a blessing font,

Figure 2 is an elevation partly in section showing the interior of the casing and the mechanism contained therein, and

Figure 3 is a sectional view showing a part of the mechanism.

The illustrated apparatus constructed and arranged according to this invention comprises the casing having the lower section 1 and removable top 2. The section 1 is provided with the door 3 through which access is gained to the interior of the casing.

The means for operating the mechanism externally consists of the button 4 located within a cupped plate 5 adjacent to the protruding spout 6 through which the water is ejected. It will be noted that as both the spout and operating button are within the cupped plate 5 or flush with the level of the edge thereof, said members cannot catch in the clothing of persons and further the relative position of the spout and button is such that no matter which finger the operator uses or in whatever position the finger may be, the ejected water will always be deposited on the finger in contact with the button. Probably after repeated use of the apparatus, there may be more or less drip, and it is arranged that all drip will pass through slot 7 in the plate 5 and fall into drip pan 8 located within the casing.

The tank 9 supported on cross members 10 within the casing, contains the water to be dispensed. This tank is covered by a loose fitting cover 11, so that air may readily enter therein to permit natural flow of the water through pipe connection 12 and which flow can be shut off or regulated if desired, by manipulation of cock 13.

The operating mechanism is simple, being composed of very few parts of which 14 is a rod capable of being given reciprocating motion by pressing in the button 4 secured at the free end of the rod. Said button is cut away at 15 so that the button may pass the spout 6. The rod 14 slides in bearings provided by the standards 16 and 16', and this rod moves inwardly against the resistance offered by coil spring 17. A plunger member is correlated with said rod 14 and this plunger member includes the short length of rod 18 which slides in a bearing provided by the standard 16. A shaft 19 having a threaded end is secured to the rod 18 so as to form a part of the plunger member. A piston 20 is carried on the free end of said shaft and this piston slides within the cylindrical head 21 forming part of the standard 16'. A lever 22 having forked ends and centrally pivoted at 23 to a lug 24 of the standard 16, engages pins 25.

within the split ends of the rods 14 and 18, and by such means the rod 14 and the plunger member are connected so as to be co-active.

5 When the button 4 and rod 14 are in the normal or inner position, the piston 20, which serves as a slide valve element effectually closes the port leading to the spout 6, and the sleeve 27 sliding in the cylinder 21, bushing 28 and stuffing box 29, prevents leakage of water at the other end of the plunger member. It will be noted the piston is capable of being given a certain independent movement relatively to the sliding sleeve 27. This independent movement is regulated by means of the adjusting nut 30 and set nut 31, and by means of this regulation a determined measured quantity of water is drawn by suction from the supply pipe during the forward movement of the plunger, and is ejected or forcibly discharged through the spout or outlet during the receding movement of the plunger, as will be hereinafter explained in connection with the operation of the improved apparatus.

The standards 16—16' which support the mechanism are mounted on the bed plate 32 which latter member is secured to the block 33 located within the casing.

The apparatus is capable of being so adjusted by means of the nut 30 so that a determined quantity of water is delivered at each operation. In the position shown in Fig. 2 (by dotted lines) the adjustment is such that there is a space between the end of the sleeve 28 and the nut 30 and which space may be increased or diminished by adjustment of the nut 30. The plunger is permitted to have an independent movement relatively to the sleeve until the nut 30 meets the sleeve and then the sleeve travels with the plunger causing the closure of the port leading from the supply pipe 12.

45 The apparatus is operated by pushing the button 4 inwardly the full extent permitted and the inward movement of the rod 14 is transmitted through the rocking lever 22, to the rod or plunger member 18. The piston 20 first moves independently of the sleeve 27, as above stated, and this movement creates suction to draw the determined quantity of water through the supply pipe 12. The nut 30 then meets and pushes the sliding sleeve forward to close the supply port, and when pressure is no longer imparted to the button 4, the coil spring 17 will cause the return of all operating parts of the mechanism back to their normal position, and the piston in its receding movement will force the water collected between the end of the sleeve and the piston, down through the spout 6. It will be understood when the piston and sleeve are in the normal position 60 the piston closes the port leading to the

spout and the ends of the sleeve and piston abut so as to close the supply port and in this position the apparatus is ready for the next operation.

It will be gathered from the above description of the means and the operation thereof, that the action of the means is positive, viz: a uniform quantity of water is ejected at each complete operation of the means without the aid of air pressure and gravity which are forces entirely relied upon to effect operation of dispensing apparatus previously proposed. And in fact, with the improved apparatus having the tight packing of the plunger member, no air whatever is admitted into the cylinder 21, consequently a perfect pumping action is obtained to eject a uniform quantity at each operation of the apparatus.

Various modifications in the construction, arrangement and operation of the improved apparatus or means, may be made without departing from the spirit of my invention and it is to be understood any such modification is covered by the claims appended hereunto.

I claim—

1. A dispensing apparatus of the class described, having mechanism comprising an operating member, a plunger member connected with said operating member so as to be co-active therewith, said plunger member being composed of a rod connected to a shaft having a piston at the free end thereof and a sleeve sliding on said shaft, a cylinder receiving said sleeve and piston, an inlet and an outlet port in said cylinder, and means for adjusting said plunger whereby a determined quantity of water is respectively drawn and ejected through said inlet and outlet ports at each operation of said operating member.

2. A dispensing apparatus of the class described comprising an operating member cooperative with a plunger member having a piston and sleeve sliding within a cylinder provided with an inlet and an outlet port, said piston moving independently of the sleeve during the initial forward and receding travel thereof respectively to open said inlet port and cause injection and ejection of a given quantity of water determined by adjustment of means permitting said independent movement, and said piston and sleeve when in their normal position closing said inlet and outlet ports.

3. An apparatus of the class described, comprising mechanism mounted on a base contained within a casing and operative by means of a push button or member located outside of said casing, said mechanism comprising parallel reciprocating members sliding in bearings provided in a pair of supporting standards secured to said base, a rocking lever centrally pivoted to one of

- said standards effecting opposite movement to said members, and a cylinder having inlet and outlet ports carried by one of said standards, and one of said reciprocating members comprising a piston and sleeve adjustable and operative relatively to each other to effect injection and ejection of a determinate quantity of water through said inlet and outlet ports.
- 10 4. A dispensing apparatus of the class described having enclosed mechanism and an external operating member therefor, said mechanism comprising a plunger member connected by power transmission means with said operating member so as to co-act 15 therewith, and said plunger member being composed of a piston, a shaft for said piston, a sleeve sliding on said shaft, and said power transmission means comprising a rod and rocking lever connecting said shaft with 20 said operating member.

Signed at New Haven, in the county of New Haven and State of Connecticut, this 19th day of August, A. D. 1922.

ALBERT W. MITCHELL.
